SAFETY PILOT SHUT-OFF

Oscar J. Leins, Milwaukee, Wis., assignor to Milwaukee Gas Specialty Company, Milwaukee, Wis., a corporation of Wisconsin

Application February 4, 1935, Serial No. 4,741

5 Claims. (Cl. 136—4)

This invention relates to safety pilot shutoffs, and more particularly is directed to shutoffs of this type for use in connection with pilot burners for hot water heaters, gas-fired furnaces, con- 5 version burners, gas ranges, space heaters and the like.

In the application of automatic control means to burners of this type, whereby the flow of fuel to the burners is automatically controlled in accordance with the sensings of a remotely disposed thermostatic device, it is essential that ignition of the fuel at the burner be positive. Also, if ignition does not occur upon the passage of fuel to the burner under the control of a remote 10 thermostat due to failure of the pilot burner, it is of the utmost importance that the fuel supply be positively shut off. This prevents danger of asphyxiation or explosion.

The primary purpose of my invention is to 20 provide a shutoff for automatically preventing flow of fuel to the burner except when the pilot burner is in operation.

In a preferred embodiment of the present invention, I provide a pilot burner head, which 25 may be generally of the type shown in the patent to Gauger, No. 1,960,777, issued May 29, 1934, and mount on this pilot head a thermocouple having its hot junction disposed in proximity to the burner port and subject to the heat of the 30 pilot flame issuing therefrom. The heat of this pilot flame generates a current in the thermocouple which flows to a holding coil of a magnetically controlled valve placed in the fuel supply line. When the pilot fails, the thermocouple 35 cools and ceases to generate current. This de-energizes the holding coil, and the valve there- upon snaps shut under spring pressure, prevent- ing any flow of fuel through the supply line to the main burner.

40 One object of the invention is to provide a convenient and simplified mounting of the thermocouple upon the pilot burner head and independently of the particular burner structure controlled by the pilot burner.

45 Another object of the present invention is to provide a novel and advantageous connection of the thermocouple to the holding coil of the shutoff valve. In a preferred form of the invention, the two conductors leading from the 50 hot thermocouple junction disposed in the path of the pilot flame comprise an insulated wire carried within a copper tube which itself forms the second conductor. The coil wound about the magnet which controls operation of the valve 55 has its terminals soldered to the tube interiorly

of the valve housing and to the conductor carried within this tube.

The adaptability of the safety shutoff unit to any type of burner renders its use practically universal for all types of heating equipment, and its positive automatic action assures safety of operation of any equipment upon which it may be installed. It is relatively simple in design, can be easily and quickly installed into operative position with respect to a burner, and has no 10 moving parts except the valve member and holding armature therefor. The use of bimetallic actuating members, rods and tubes, liquid-in-bulb expansion members and other control mechanisms has been entirely eliminated by the present construction. As there is no rigidity necessary to be maintained for operation of the device, the structure is extremely flexible in its 15 adaptability to the particular burner or heating equipment upon which it is to be installed.

20 Further, the unit is self-contained, requiring no auxiliary external batteries or circuit connections, relays, or the like, and the control is effected within the unit only by means of the current generated by a relatively small pilot flame. 25 There is no necessity for adjusting or calibrating the unit to each installation, as it is independent of the particular type of burner or heating equipment to which it is applied.

30 Other objects and advantages of the present invention will appear more fully from the following detailed description, which, taken in connection with the accompanying drawing, will disclose to those skilled in the art the particular construction and operation of a preferred form 35 of the present invention.

In the drawing:

Figure 1 is a diagrammatic view of the present invention as applied to a hot water heater;

Figure 2 is an enlarged view, partly in section, 40 showing the safety shutoff unit and its mounting upon a pilot burner;

Figure 3 is a vertical sectional view through the shutoff valve; and

Figure 4 is a detail sectional view through the 45 thermocouple tip.

In Figure 1 I have disclosed a hot water heater structure comprising a housing or drum 5, having a fire box 6 and a suitable supporting base 7. The burner for heating the water is shown 50 at 8, and is connected through the mixing chamber 9 to a fuel supply line shown generally at 10. Mounted in the fuel supply line 10 is the safety shutoff valve indicated generally at 12, and anterior to the valve is the pilot burner 55

conduit 13 leading from the fuel supply pipe 10 to the pilot burner head. The thermocouple 15 is carried by the head 14, and is connected to the valve 12, whereby upon extinguishment 5 of the pilot burner at the head 14, the current generated by the thermocouple ceases, and the valve 12 closes, shutting off the flow of the fuel from the supply line 10 to the mixing chamber 9 of the burner 8, whereby no fuel will escape 10 to the burner.

Considering now in detail the structure of the shutoff unit, in Figure 2 I have shown the pilot burner head 14 in section. This head includes an air inlet opening 18, a bushing 19 threaded 15 into one end of the head and adapted to receive the threaded end of the pilot burner conduit 13 leading to the fuel supply line, a pilot jet or spud 20 within the bushing 19 and directed substantially axially of the head 14, the jet 20 having a small jet opening 22 for directing a jet of gas from the conduit 13 into the Venturi bushing 23 carried within a reduced portion of 25 the head 14. The jet of gas passing into the bushing 23 draws with it air from the air intake chamber 18, and the mixture of gas and air passes into a mixing chamber 24, from which it issues through the laterally and vertically directed ports 25 and 26 respectively, and is ignited to burn as a pilot flame, shown at 27. This 30 pilot flame is preferably relatively small, of the order of 100 B. t. u. to provide economy in the operation of the unit.

The innrush of relatively cool air into the air intake chamber 18 caused by the suction produced by the jet of gas 22 passing into the Venturi bushing 23 serves to cool the jet 20, whereby it does not become excessively heated, and fouling and choking of the supply nozzle is eliminated. The Venturi bushing 23 provides for sufficient suction to produce an adequate amount of air flow into the mixing chamber 24, whereby the proper amount of air will be mixed with the fuel to give the desired pilot flame at the ports 25 and 26.

45 The burner head 14 has an upwardly projecting clamping portion 28, which is provided with a suitably recessed portion receiving the exterior tubular portion 29 of the thermocouple, there preferably being a clamping screw 30 passing 50 through the clamping support 28 to secure the thermocouple 29 positively in position upon the burner head 14. The shoulder 32 of the tube 29 provides an abutment whereby the positioning of the thermocouple junction 33 with respect to 55 the burner port 26 is positively determined.

Considering now in detail the structure shown in Figure 4, the thermocouple junction 33 comprises a welded junction between two dissimilar metals, there being an outer enveloping tubular member 34, which may be formed of constantan, or chromel, and the enclosed member 35, which is formed of the opposite metal.

The welded junction 33 being disposed directly in the path of the pilot flame from the port 60 26, comprises the hot junction of the thermocouple, and the enclosing tubular member 34 is connected with the copper tubing member 29, which is preferably enlarged adjacent the clamped portion thereof whereby the member 70 34 is received in telescoping engagement therewith, the two members being preferably welded or otherwise suitably secured together. The outer element 34 is highly resistant to heat, and completely encloses and protects the inner element 75 from the heat of the pilot flame. The

inner element is welded, as shown at 36, to an insulated conductor 37, the conductor 37 being preferably an asbestos insulated wire carried within the tube 29. The copper tube 29, at its remote end, extends into a copper bushing 38 5 having an expanded cylindrical section which enters into an opening formed in the upper housing 39 of the valve assembly.

Considering now in detail Figures 2 and 3, which disclose the internal construction of the valve 12, the cup-shaped housing 39 is provided, at its upper end, with an inwardly extending boss portion 40 forming a central rib or web. This web provides a supporting base for a bracket member 42 which is secured thereto by means of 15 the screws 43. The bracket member 42 is adapted to support a U-shaped magnet 44 in depending position below the web 40. The magnet is preferably of a special alloy which is noncorrosive, and has high permeability, with minimum 20 retentivity of magnetism. Each leg of the magnet 44 has mounted thereon a coil of insulated wire, indicated at 45, and the end terminals of the coils 45 are connected to the conductor 37 at 46 and to the inner projecting portion of 25 the bushing 38 at 47, preferably by soldered connections thereto. This connects the thermocouple 15 to the coils 45 surrounding the legs of the magnet 44. Preferably an insulating sleeve 41 extends about the conductor 37 enclosing the 30 connection 46, projecting a considerable distance inwardly of the housing 39.

The cover or dome shaped housing 39 is preferably threaded on to a projecting boss 48 formed integral with a valve housing member 49. The 35 valve housing 49 is provided with an inlet chamber 50 and an outlet chamber 52 separated by a partition wall 53 having a valve seat 54 formed about the valve opening therethrough. The inlet chambers 50 and 52 are adapted to be connected 40 to the fuel conduit 10 in any well known manner, and the fuel passes from the inlet chamber 50 past the valve opening and then through the outlet chamber 52 to the burner 8.

Pinned or otherwise suitably secured within the 45 lower end of the dome-shaped housing 39 is a guide member 55, which member has upwardly projecting spaced leg portions 56 serving as guides for reciprocatory movement of the carrier member 57 therein. Preferably four such guiding legs 50 are provided.

The carrier member 57 is adapted to provide suitable carrying means for the armature 58, which armature is preferably formed of a special alloy which is noncorrosive, has a high degree of 55 permeability, and minimum retentivity. The armature 58, as shown in Figures 2 and 3, is securely held by the carrier member 57, the upwardly projecting portions of the carrier member being bent over, as shown at 58' in Figure 2, 60 to secure the armature in position.

The lower end of the carrier member 57 is provided with a downwardly and inwardly offset portion 59, which is adapted to have universal movement about an annular groove 60 formed in 65 the valve stem member 62. This valve stem member 62 has axial reciprocatory movement within the guide member 55, and at its lower end is provided with a valve member 63 universally mounted about an annular groove in the lower end of the 70 stem 62. The valve member 63 has an upwardly extending recessed portion in its lower surface receiving the nut 64, which nut is adapted to secure a leather facing member 65 to the 75 annularly recessed portion of the valve member 63,

whereby a leather faced valve member is provided for engagement with the valve seat 54.

The valve member 63 is provided with an upwardly extending cylindrical boss portion about which is biased a coiled spring member 66, which spring member at its opposite end seats against a washer 67 press-fitted into an annular recess formed in the lower extending end of the guide member 55. The washer 67 serves as an additional guide for the valve stem 62, and is adapted to place the packing disposed thereabove within the recess in compression about the valve stem to prevent leakage of gas from the inlet chamber 50 upwardly past the valve stem into the dome-shaped housing 39.

The spring member 66 is adapted to urge the valve member 63 constantly into engagement with the valve seat 54, so that upon deenergization of the coils 45, the magnet 44 becomes deenergized, releasing its grip upon the armature 58, and allowing the valve member 63 to seat against the valve seat 54 under the pressure of the spring 66.

In the operation of the device, during such times as the pilot flame from the ports 25 and 26 is ignited, the heat imparted to the thermocouple junction 33 will be sufficient to maintain the coils 45 of the magnet 44 energized, whereby the magnet is sufficiently energized to maintain the armature 58 in attracted position across the lower end of the leg portions thereof, against the tension of the spring member 66. This holds the valve open during all times that the pilot burner is ignited. Upon extinguishment of the pilot burner, the thermocouple 33 rapidly cools, and as a result the generation of current is discontinued, and the magnet 44 becomes deenergized. Due to the minimum retentivity of the magnet and armature, the armature is immediately released from the lower end of the magnet, and drops downwardly therefrom under the pressure of the spring 66, the valve member 63 at the same time shutting off flow of fuel through the valve 12 to prevent further flow of fuel to the burner 8 should the secondary thermostatically controlled anterior fuel metering valve be in open position.

Although the magnet 44, when the armature 58 is in engagement therewith, may be sufficiently energized to maintain the armature in attracted position against the pressure of the valve spring 66, nevertheless it is not capable of drawing the armature 58 upwardly from valve closed position. In order, therefore, to provide for opening of the valve during initial operation, a reset button 70 is provided, which button 70 is mounted at the upper end of a reset plunger 72 extending through the lower end of the valve 49. The plunger 72, at its lower end, is provided with a push button 73, which button is preferably recessed as shown at 74 to provide a seat for a spring member 75 normally urging the plunger outwardly of the valve housing.

Outward movement of the plunger is limited by engagement of the lower annular end of the button 70 upon the boss forming the guide for the plunger 72. The spring 75, at its upper end, is biased against a washer 76, which washer is adapted to engage suitable packing disposed in an annular recess about the plunger 72 and to force this packing into engagement with the lateral surface of the plunger, whereby leakage of gas from the outlet chamber 52 of the valve housing 49 past the lateral surface of the plunger 72 is prevented. In order to prevent accidental operation of the reset button 70, and to protect the reset plunger and push button 73 against

mechanical injury, a gas tight cap 77 is threaded about the lower extending portion of the valve housing 49, and serves to form an enclosure about the push button 73, so that it is necessary to remove the cap member 77 before the plunger 72 can be actuated to provide for engagement of the button 70 with the nut 64 of the valve member to provide for moving the valve member upwardly to place the armature 58 in attracted position.

After the valve 12 has once been closed due to failure of the pilot flame, no fuel can flow to the burner 8, until the pilot flame has been reestablished. Thus, when the pilot flame 27 is to be reignited, it is necessary to unthread the cap member 77, and manually push the plunger 72 upwardly to move the valve stem 62 upwardly into position whereby the armature 58 is engaged with the lower end of the magnet 44. By holding the plunger 72 in raised position until such time as the pilot flame has sufficiently heated the thermocouple 33 to provide for complete energization of the coils 45 by the current generated at the thermocouple, it is possible to have the magnet 44 thereafter hold the armature 58 in attracted position, and the plunger 72 can then be released, and the enclosing cap 77 rethreaded over the lower end thereof. As long as the pilot flame remains ignited, thereafter, the thermocouple will energize the coils 45 to an extent such that the armature will be maintained in attracted position across the ends of the magnet 44. Thereafter, upon extinguishment of the pilot flame, the magnet 44 becomes deenergized and the valve 63 closes under spring pressure.

It is thus apparent that I have provided a novel type of pilot shutoff unit, which is capable of producing a positive and accurate control of the flow of fuel to a main burner or the like directly in accordance with the operation of the pilot burner, and which employs no moving parts at the pilot burner, and therefore is relatively flexible and capable of easy installation, and can be employed without the necessity of separate supporting means or the like. In addition, the tube 29 can be made of any desired length, so that the valve 12 may be disposed in any desired position in the fuel conduit 10 independently of the positioning of the thermocouple, whereby the adaptability of the unit to various types of heating equipment is increased. Further, it will be noted that, by reason of the novel manner in which the current generated at the thermocouple junction is transmitted to the coils of the electrically controlled valve, only one insulated conductor is required, and the use of the copper tube 29 as a conductor simplifies the design of the unit, and at the same time provides a substantially secure and positive connection between the thermocouple and the valve. The inherent rigidity of the tube is such that it may independently support the thermocouple if desired. The particular construction of the valve is such that it is capable of rapid and positive operation in accordance with the actuation of the armature, and will positively shut off the flow of fuel through the valve when the thermocouple is not being heated by the pilot flame.

It is apparent that certain modifications in design and construction of the component parts of the present invention may be made without in anywise departing from the underlying principles thereof, and I therefore do not intend to be limited to the exact details shown and described, but only insofar as defined by the scope and spirit of the appended claims.

I claim:

1. A thermocouple and lead connection therefor comprising an inner metallic thermocouple member, an internally disposed lead conductor connected to said inner thermocouple member to form an internal thermal junction, single wall metallic tubular means enclosing said inner thermocouple member and said internal thermal junction and comprising an outer metallic tubular thermocouple member joined to said inner thermocouple member to form a second thermal junction adapted to be heated and an outer tubular lead conductor connected to said outer tubular thermocouple member to form a third thermal junction, said outer tubular thermocouple member having its outer surface externally exposed throughout substantially its entire length and with said outer tubular lead conductor constituting a single wall enclosure about said inner thermocouple member and said internal thermal junction of a character throughout the extent of said inner thermocouple member and said internal thermal junction thermally to insulate said internal thermal junction and maintain the heat transmitted to said internal thermal junction when said second thermal junction is heated so that the difference in temperature between said internal thermal junction and said second thermal junction is more quickly reduced when the heating of said second thermal junction is discontinued.
2. A thermocouple and lead connection therefor comprising an outer metallic tubular thermocouple member, an inner metallic thermocouple member disposed within said outer thermocouple member and rigidly joined at one end to one end of said outer thermocouple member to form a thermal junction adapted to be heated, the opposite end of said inner thermocouple member extending beyond the opposite end of said outer thermocouple member, an inner lead conductor joined to the extending end of said inner thermocouple member to form an internal thermal junction beyond the end of said outer thermocouple member, and an outer tubular lead conductor enclosing said inner lead conductor and said internal thermal junction and rigidly joined to said outer thermocouple member between said first and second thermal junctions, said outer tubular lead conductor forming a single wall enclosure about said internal thermal junction and the adjacent end of the internal thermocouple member with the inside of said single wall enclosure directly exposed to the internal thermal junction and the outside of said single wall enclosure externally exposed, said single wall enclosure being of a character thermally to insulate said internal thermal junction and maintain the heat transmitted to said junction when said first thermal junction is heated so that the difference in temperature between said first thermal junction and said internal thermal junction is more quickly reduced when the heating of said first junction is discontinued.
3. A thermocouple and lead connection therefor comprising an outer metallic tubular thermocouple member, an inner metallic thermocouple member disposed within said outer thermocouple member and rigidly joined at one end to one end of said outer thermocouple member to form a thermal junction adapted to be heated, the opposite end of said inner thermocouple member extending beyond the opposite end of said outer thermocouple member, an inner lead conductor joined to the extending end of said inner thermo-

couple member to form an internal thermal junction beyond the end of said outer thermocouple member, an outer tubular lead conductor enclosing said inner lead conductor and said internal thermal junction and rigidly joined to said outer thermocouple member between said first and second thermal junctions, said outer tubular lead conductor being of reduced diameter closely to enclose said inner lead conductor and enlarged adjacent the end joined to the outer thermocouple member to form a single wall enclosure of enlarged diameter about said internal thermal junction and the adjacent end of the inner thermocouple member with the inside of said single wall enclosure directly exposed to the internal thermal junction and the outside externally exposed, said single wall enclosure being of a character thermally to insulate said internal thermal junction and maintain the heat transmitted to said junction when said first thermal junction is heated so that the difference in temperature between said first thermal junction and said internal thermal junction is more quickly reduced when the heating of said first junction is discontinued.

4. In combination, a burner head adapted to be connected to a fuel supply conduit and having flame port means therein, a thermocouple comprising an outer metallic tubular thermocouple member, an inner metallic thermocouple member disposed within said tubular thermocouple member and joined to the end thereof to form a first thermal junction, a tubular conductor member connected to said outer tubular thermocouple member to form a second thermal junction, an internally disposed conductor extending through said tubular conductor and connected to said inner thermocouple member to form an enclosed third thermal junction for the thermocouple, said tubular conductor member and said internally disposed conductor forming a lead circuit connection for the outer and inner members of the thermocouple, and a bracket member on said burner head and cooperating with one of said tubular members to support the thermocouple in position on said burner head with the first thermal junction between said inner thermocouple member and said tubular thermocouple member in proximity to the flame port means in said burner head.

5. In combination, a burner head adapted to be connected to a fuel supply conduit and having a flame port therein, an outer tubular conductor member constituting a lead tube, an inner lead conductor extending through said lead tube, a thermocouple comprising an outer metallic tubular thermocouple member and an inner metallic thermocouple member disposed therein and joined to said outer thermocouple member to form a thermal junction, said outer tubular conductor member being joined to the outer tubular thermocouple member to form a second thermal junction and said inner lead conductor being joined to said inner thermocouple member to form a third thermal junction, and a bracket member on said burner head and cooperating with one of said tubular members to support the thermocouple with the thermal junction between the inner thermocouple member and the outer thermocouple member in proximity to the flame port means in the burner head, said bracket member enclosing the thermal junction between the outer tubular conductor member and the outer tubular thermocouple member.
